UNITED STATES PATENT OFFICE.

GEORGE W. WAITT, OF SAN FRANCISCO, CALIFORNIA.

TAPPET FOR STAMPING-MILLS.

SPECIFICATION forming part of Letters Patent No. 631,535, dated August 22, 1899.

Application filed September 6, 1898. Serial No. 690,369. (No model.)

To all whom it may concern:

Be it known that I, GEORGE W. WAITT, a citizen of the United States, residing at San Francisco, in the county of San Francisco and State of California, have invented certain new and useful Improvements in Tappets for Stamping-Mills, of which the following is a specification.

My invention relates to the fastening or clamping of tappets to the stems of stamp-mills used in crushing gold and silver ores or other material; and it consists of an adjustable clamping device, as hereinafter explained and as illustrated in the accompanying drawings, in which—

Figure 1 shows a side elevation of the tappet, part being broken away. Fig. 2 is a section on line $x-x$ of Fig. 1. Fig. 3 is a similar section representing the same system of clamping, but shows two gibbs bearing upon the stem instead of one, as shown in Fig. 2. Fig. 4 is a detail of the clamping-band.

Tappets are now and have been heretofore secured to the stems which carry the shoes of stamp-mills by means of wedges, causing frictional contact to hold the tappet to the stem. These wedges are comparatively effective for the purpose, but the use of them is attended by difficulties both in the application and removal of the tappet up or down on the stem, according to the desired amount of drop of the stamp for the class of ore to be crushed and also change on account of the wearing away of the shoes and dies. Another objection to the wedge-fastening is that the constant jar of the stamp in its drop loosens the wedges, necessitating the readjustment of the tappet to its proper position on the stem. Another contingency is driving the keys or wedges so hard as to often split off the side of the tappet and ruin it, resulting in a loss of time and expense in replacing another, causing not only the loss of tappet and time in replacing, but a loss in output of the mill. Another loss in time is in changing the tappets up or down to compensate for the wear of the shoes and dies.

My invention is designed to avoid the above contingencies of delay and breakage and saving much time in adjustments and no contingency of bursting the tappet in its fastening to the stem, which is often done.

My invention is designed to avoid the above contingencies, and this is effected as herein-after explained.

In the drawings the tappet is shown more clearly in Fig. 1. It consists of a cylindrical sleeve A, which is fitted to receive the stem and has on one or both ends a flange B, against which the cam bears in lifting. The interior wall of the sleeve is chambered out longitudinally to receive the gib or gibbs, as shown at d , Figs. 1 and 2. These chambers or recesses in the wall may be single and on one side, as shown in Fig. 2, or duplicate and arranged on each side of a central line between the clamps, as shown in Fig. 3. In the recess, whether single or duplicate, is placed a gib, fitting in the recess and having a stud e , of the width of the gib d , extending into a circumferential groove f , which receives the clamping-band g , the arrangement of the parts being such that the band g when drawn together or contracted about the sleeve bears upon the stud and forces the gib against the stem. The band g is preferably made in two parts, hinged together at l and provided with outturned ends h , perforated to receive a bolt having a nut m , by which force is applied to draw together the parts of the clamp and press the gib or gibbs upon the stem. The nut is held by a key k against turning. The gib is held in the recess against longitudinal and lateral movement, and when the nut m is turned the gib is clamped by the band and pressed against the stem with frictional contact sufficient to hold it in place on the stem when acted on by the cam.

I prefer the arrangement of duplicate gibbs shown in Fig. 3. These are placed on each side of a central line drawn between the two parts of the band and near the movable ends. More contact-surface is thereby obtained and a wedging action is produced by the band upon the gib projection.

I have shown two bands, these being preferable; but they are exact duplicates and bear on studs of the same form on the gib.

I claim—

1. A tappet having an interior chamber or recess in its wall, and a groove around it with an opening from the recess to the groove, a gib having a stud or boss projecting into the groove, a band in the groove and mechanism

for drawing upon the band and causing it to press upon the gib, the parts being constructed and combined, substantially as described.

2. The combination with the sleeve of the 5 tappet having recesses therein, a two-part hinged band, a gib arranged in each recess, one near each of the free ends of the band, said sleeve having openings from the recesses through which the band and gibs are de-

signed to contact, and means for drawing the parts of said band together, substantially as described.

In testimony whereof I affix my signature in presence of two witnesses.

GEORGE W. WAITT.
